(57) CLAIM

The ornamental design for an air freshener with wood grain backing and interchangeable scented pad, as shown and described.

DESCRIPTION

FIG. 1 is a rear elevation view of the air freshener with wood grain backing and interchangeable scented pad, showing my new design;

FIG. 2 is a front elevation view thereof;

FIG. 3 is a left side, elevation view thereof;

FIG. 4 is a right side, elevation view thereof; and,

FIGS. 5 & 6 are respective bottom plan and top plan views thereof.

The broken lines are for exemplary illustrative purposes only and form no part of the claimed design.
